UNITED STATES PATENT OFFICE.

THOMAS T. LEWIS, OF PHILADELPHIA, PENNSYLVANIA.

DESIGN FOR A BATTERY-PLATE.

SPECIFICATION forming part of Design No. 30,909, dated May 30, 1899.

Application filed May 1, 1899. Serial No. 715,239. Term of patent 14 years.

To all whom it may concern:

Be it known that I, THOMAS T. LEWIS, a citizen of the United States, residing in the city and county of Philadelphia, State of Pennsylvania, have invented and produced a new and original Design for a Battery-Plate, of which the following is a specification, reference being had to the accompanying drawings, forming part thereof.

- 10 The leading feature of my design for a battery-plate is a plate having outwardly-deflected bars on opposite faces thereof, the deflections of one face alternating with those of the other face.
- 15 Figure 1 represents a plan view of a battery-plate embodying my design. Fig. 2 represents a longitudinal section on line xx , Fig.

1. Fig. 3 represents a transverse section thereof on line yy , Fig. 1.

In the drawings, A designates a battery-plate, and B and C designate bars on opposite faces thereof, said bars being deflected outwardly and alternating in their deflections on said opposite faces.

Having thus described my invention, what I claim as new, and desire to secure by Letters Patent, is—

The design for a battery-plate, as herein shown and described.

THOMAS T. LEWIS.
